DESIGN FOR A CONDIMENTS SHAKER

William E. Mackelfresh, Jr., Chicago, Ill., assignor to Owens-Illinois Glass Company, Toledo, Ohio, a corporation of Ohio

Application June 9, 1937, Serial No. 69,763

Term of patent 14 years

To all whom it may concern:

Be it known that I, William E. Mackelfresh, Jr., a citizen of the United States, residing at Chicago, in the county of Cook and State of Illinois, have invented a new, original, and ornamental Design for a Condiment Shaker, of which the following is a specification, reference being had to the accompanying drawing, forming a part thereof.

In the drawing:

Fig. 1 is a side elevational view of a condiment shaker showing my new design.

Fig. 2 is a bottom plan view thereof.

I claim:

The ornamental design for a condiment shaker substantially as shown.

WILLIAM E. MACKELFRESH, JR.
